UNITED STATES PATENT OFFICE

RINGHALD PER ALFRED ANDERSSON, OF TABY, STOCKHOLM, SWEDEN

ADJUSTABLE SLICING KNIFE

Application filed August 22, 1927, Serial No. 214,727, and in Sweden January 5, 1927.

This invention relates to an improvement in adjustable slicing knives for cutting meat, bread, cheese or the like in slices and consists therein that a shaft fastened to the knife 5 is provided with a sliding block 8 slideable and turnable on the shaft and provided with a guiding bar the inside of which is parallel to the knife blade and which guiding bar may be set at different distances from the blade of the 10 knife.

In the accompanying drawing Fig. 1 shows a knife provided with an arrangement according to the invention and seen from the side. Fig. 2 is a plan view of the same knife. 15 Fig. 3 shows the same knife with a modified form of the arrangement.

The knife is of the usual form on the market, and in the drawing the handle is indicated by 1, 2 is the fastening or knife-ring 20 and 3 the blade.

Referring to Figs. 1 and 2, in the middle of the fastening ring is bored a horizontal hole 4, in which a shaft 5 is riveted. On the free end 19 of the shaft is a slideable block 8 to which is fastened a stop-arm 9 which rests against the back of the blade or the upper edge of the knife ring and may have that form shown in the drawing, as well as a guiding bar 10 the inner side 12 of which is parallel with the 25 length of the blade. The stop-arm has for its object to hold the sliding block with the guiding-bar in a certain position in relation to the knife-edge 13 when the sliding block is actuated by a spring 11. This spring 11 is 30 fastened at one end 14 to the shaft or to the fastening ring 2 and is wound around the shaft. Its other end 15 is fastened to the sliding block 8. When the spring is tensioned it thus forces the sliding block to turn downwards until the stop-arm 9 rests against the 35 knife ring. The guiding bar is bent to the form shown in the drawing and is fastened by its ends 16 and 17 to the sliding block 8, but may of course also have another form.

40 In order that the guiding bar by its inner edge 12 may be set at different distances from the knife-blade the shaft 5 at its outer free end 19 is threaded and provided with an adjusting nut 20. When the nut 20 is tightened the sliding block 8 is moved along the shaft 5 in to-

wards the knife edge, whereby the helical spring 11 is compressed. If the nut is screwed outwards the spring forces the sliding block 45 outwards and the guiding bar on the sliding bar 8 is removed from the knife blade. 55

Another embodiment is shown in Fig. 3. This embodiment is substantially like that described above, but here the stop-arm 9¹ is provided with vertically arranged grooves or ridges 24, into which catches one end 25 of a 60 helical spring 11¹ wound around the shaft 5¹ carrying the sliding block 8¹ and fastened to a shoulder 6 on the said shaft. The free end 25 of the spring is formed into an arm provided with a ball 26 or the like which may be depressed by the finger, so that the free end 25 of the spring comes out of catch with the grooves 24 when the sliding block 8¹ with the 65 guiding bar is to be moved on the shaft 5¹. The sliding block 8¹ is removable by this locking device and may thus be removed when the guiding bar is not to be used. 70

Instead of being riveted to the knife ring 2 the shaft 5 may be fastened to a loose clamp or fork, which is screwed on to the fastening ring 75 2, so that the whole device may be removed or fastened to any knife.

The sliding block may have the form which is shown in the drawing. In Fig. 3 there is shown a horizontal sleeve 27 inserted in the 80 sliding block and having a certain length, the sleeve being slit lengthwise as indicated at 27^a and yieldingly clamping upon the shaft with the sliding block.

Having now described my invention, what 85 I claim as new and desire to secure by Letters Patent is:

1. An adjustable slicing knife including a blade, a handle and a ring fastening the blade to the handle, a horizontal shaft riveted to the 90 ring at right angles to the length of the knife blade and on which shaft is slidably arranged a lockable and settable sliding block, provided with a guiding bar fastened to it and arranged parallel to the blade, the inner edge of which 95 guiding bar rests against the end surface of the object to be cut, the sliding block with the guiding bar being turnable on the shaft and provided with a helical spring one end of which is fastened to the shaft and the other 100

end of which is adapted to turn the knife bar downwardly with relation to the knife edge, the sliding block also being provided with a stop-arm fastened to it, which stop-arm rests against the back of the blade and determines the position of the spring actuated guiding bar in relation to the knife edge.

2. A locking device for the sliding block mentioned in the claim 1, characterized thereby that the stop-arm fastened to the sliding block is provided with grooves arranged parallel to the cutting surface of the blade, and that the helical spring includes an arm, which arm catches into the grooves in the stop-arm, when the sliding block with its guiding bar is in its fixed position in relation to the blade and also acts upon the stop-arm, so that it rests against the back of the blade or the fastening ring.

20 In witness whereof, I have hereunto signed my name.

RINGHALD PER ALFRED ANDERSSON.
